UNITED STATES PATENT OFFICE.

CHARLES A. JUENGST, OF CROTON FALLS, NEW YORK, ASSIGNOR TO AMERICAN ASSEMBLING MACHINE COMPANY, OF MEMPHIS, TENNESSEE, A CORPORATION OF DELAWARE.

BOOK-COVERING MACHINE.

Application filed March 14, 1924. Serial No. 699,164.

To all whom it may concern:

Be it known that I, CHARLES A. JUENGST, a citizen of the United States, and a resident of Croton Falls, in the county of Westchester and State of New York, have invented certain new and useful Improvements in Book-Covering Machines, of which the following is a specification, reference being made to the accompanying drawings, forming a part thereof.

My invention relates to machines for applying covers on books or pamphlets after they have passed from the signature gathering or other machine, such as a stitcher or sewing machine. Automatic book covering machines as now built and operated are usually connected with an automatic feeder timed to continuously feed the successive books to the continuously moving conveyor in the book covering machine by which the covers are applied to the backs of the traveling books so that the operation of the machine through the successive cycles will be both automatic and continuous throughout, thereby dispensing with necessity of constant attention by the operator.

The main objects of my present invention are, among other things, to provide an improved and simplified book covering machine of this character whereby the path of the books through the machine may be maintained substantially in a horizontal straight line; also to provide means whereby the coacting book clamps used to hold the books firmly in position on the carrier and mounted in pairs thereon may have an opening and closing movement in mutual parallelism and may collectively move in vertical alinement with the line or path of the successive books advancing through the machine. Such feature of improved construction and coordination between the successive devices employed for applying the covers to the books precludes any disarrangement in the several books in their straight line progress through the machine, and also enables the covers to be applied to the lowermost backs with greater accuracy and register while the books are held and forwarded by the successive pairs of clamps in upright position from one operating device to another. By my improvement the books may be speedily handled and the

covers applied with great effectiveness and precision.

Further objects and advantages will hereinafter be set forth and be particularly pointed out in the claims; my improvements may be embodied either in the preferred form of book covering machine herein shown or in various modified forms to fit the particular conditions of usage in different types of machines of this general character.

Of the drawings, Fig. 1 is a side elevation of my improved machine;

Fig. 2 is a partial top plan-view of Fig. 1;

Fig. 3 is an end elevation of the feeder end of the machine;

Fig. 4 is an end elevation of the delivery end of the machine;

Fig. 5 is a top plan view of a pair or set of book clamps;

Fig. 6 is an enlarged section taken on the line 6—6 of Fig. 1;

Fig. 7 is an enlarged section taken on the line 7—7 of Fig. 1;

Fig. 8 is an enlarged section taken on the line 8—8 of Fig. 1; and

Fig. 9 is an enlarged top plan view of the connecting portions of the book clamps showing their arrangement to comprise the endless carrier chains for advancing the books through the machine.

Similar numerals refer to similar parts throughout the several figures.

Referring to the drawings, and more particularly Fig. 1, the standards 10 support the two-spaced-apart cross-shafts 11 and 12 on which are affixed separate pairs of spaced-apart sprockets 13 and 14 respectively as shown in Figs. 3 and 4. Each of these two sprockets 13 and 14 is vertically disposed and sufficiently spaced from the other to permit of the opening and closing of the book-clamps hereinafter to be described. The shaft 12 is rotated by bevel gear 15 which meshes with the bevel gear 16 on the upright shaft 17 on the lower end of which is secured the bevel gear 18 engaging the bevel gear 19 driven by the electric motor 20, or other suitable source of power, all as shown in Fig. 4.

The successive book clamps are hinged together to form an endless loop book conveyor passing around the pairs of sprockets

13 and 14 as shown by the arrow in Fig. 1.

Each book clamp comprises two vertical disposed members 21 and 22 adapted to engage the sides of the books carried, the member 21 being journaled at each end to the cross-bars 23 as shown in Fig. 5, while the movable member 22 is slidably mounted at one end on the cross-bar 23 while the other end is slidably mounted on the shaft 24. 5 One end of the shaft 24 is secured in the member 21, while the opposite end is secured in the link-member 25 as shown in Figs. 5 and 9. The link members 25 are journaled to the cross-bars 23 to 10 form one side of the endless book-conveyor, and the springs 26 and 27 coiled about the cross-bars 23 and cross-shafts 24 normally exert a closing pressure on the book-closing movable members 22 as shown in Fig. 5. 15 20 Pivoted to each end of the cross-bars 23 are the horizontal guide rollers 28 and 29 respectively adapted to fit in the slots 30 and 31 formed in the sprockets 13 and 14 by which the successive pairs of book-clamps 25 forming the book-conveyor are driven by such sprockets when revolved in a counter clockwise direction as shown in Fig. 1. Each movable member 22 carries the cam-roller 32 which by engaging suitably disposed cams 33 and 34 opens the successive book clamps against the tension of the springs 26 and 27, as such book clamps progress through the machine.

The books are fed to my machine in up-right position with their backs lowermost by any suitable mechanism. In the embodiment shown in Fig. 1, the conveyor belt 35 passing around the pulley 36 journaled on the standard 10 advances the successive 35 books 37 longitudinally extended along the side guides 38 and 39 adjacent the periphery of the sprocket 12 ready to be seized by the book clamps as shown in Figs. 1 and 3.

Arranged beneath the book conveyor is 40 the glue pot 40 in which is rotatably secured the glue roller 41 which feeds the glue to be applied to the backs of the successive books 37 carried by the conveyor in contact with the roller 41.

50 The covers 42 are fed up to the cover presser drum 43 by the endless carrier 44 having spaced-apart push fingers 45 to convey the separate covers advanced to the carrier 44 by any convenient form of feeder, in 55 the present embodiment, a continuous feeder 46 suitably located beneath the book conveyor, as is shown in Fig. 1.

The covers 42 pass up successively between the fingers 45 on the upper run of the carrier 44 and then around the drum 43 where they are applied gradually to the backs of the books, the drum pressing the cover progressively throughout its length. In the forward travel of the book-clamps on the conveyor the books 37 then pass to the cover

breaker 47 located beneath the book conveyor as shown in Fig. 1. This cover breaker 47 is movable horizontally so that when the book 37 comes opposite this cover breaker the jaws of the breaker move inwardly to 70 break the cover in the usual manner.

The books then pass to the endless delivery conveyor 48 mounted on the pulleys 49 and 50 journaled in the standards 10 by which conveyor the separate books travel 75 along the delivery chute 51 to fold up the cover flaps around the book as shown in Figs. 6, 7 and 8, the sides 51^a and 52 being inclined for this purpose, along the delivery conveyor 48 to transfer the covered books to 80 any convenient form of stacker 53 located at the forward end of the standards 10 as shown in Fig. 1.

The cam 33 is affixed to the bracket 54 secured to the standard 10 (Fig. 3) so as to 85 open the normally closed book clamps as shown when the latter begin their lower run. As shown in Fig. 1, the cam 33 starts at a point before the book clamps reach the side guides 38 and 39, and such clamps close 90 on the book at the end of the forward run of the belt 35. In like manner the cam 34 is affixed to the bracket 55 secured to the standard 10 (Fig. 4) so as to release the books as they pass into the delivery chute 95 51 (Fig. 6). The cam 34 starts to open the book clamp gradually and holds them in open position until the book with its out-spread cover 42 has reached its Fig. 7 position on the conveyor 48.

100 It will seem from the foregoing that the forward travel of the books 37 when fed from the belt 35 to the book clamps on the conveyor and then through the successive operating devices for applying the covers to the books to the chute 51 is in a horizontal straight line with the book clamps opening and closing in mutual parallelism with the sides of the books. Furthermore such

clamps have a revolving movement in the endless conveyor in vertical alinement with the path of the successive books through the machine. By such construction and operation the clamps have a combined transverse movement in opening and closing which 110 produces an exceptionally firm hold on the book, and such clamps also move in vertical or upright position, shown more particularly in Fig. 3, as they are brought into accurate register with the book 37 advanced by the conveyor belt 35; thereafter they are delivered with their covers 42 in the chute 51 in perfect alinement as shown in Fig. 6 with the books travelling in a horizontal straight path throughout the entire machine. 115

120 My improved book covering machine is simple in construction and pronounced advantages are attained by having the various devices for handling and operating on the backs of the books held in upright position 125 130

arranged as shown in this preferred embodiment of my invention with the books being forwardly moved and delivered with great smoothness in their proper position to the 5 stacker 53.

However, my invention, in its broadest aspects, is not limited to the particular constructions shown, nor to any specified arrangement, since many modifications and 10 alterations may be made in the details of the structures shown without departing from the underlying principles of the invention and without sacrificing its chief advantages.

15 I claim as my invention:

1. In a book covering machine, a looped endless book conveyor having a continuous advancing movement in a vertical plane, means for feeding books in upright position 20 in parallelism with the conveyor and at the beginning of the lower run thereof, and means for holding and releasing the books at the end of the lower run whereby the latter travel only in a substantially horizontal, straight-line path through the machine.

2. In a book covering machine, a looped endless book conveyor having a continuous advancing movement in a vertical plane, means for feeding books in upright position 25 in parallelism with the lower run of the conveyor, and means for holding and releasing the books only through the lower run of the conveyor, whereby the latter travel in a substantially horizontal straight-line path through the machine.

3. In a book covering machine, an endless book conveyor having a continuous longitudinal advancing movement in a vertical plane, book-clamps carried thereby having 40 an opening and closing movement at right angles to the conveyor movement, means for feeding books in the same direction and in parallelism with the lower run of the conveyor, and means for applying covers to 45 the books while held by the book-clamps.

4. In a book covering machine, an endless book conveyor having a continuous longitudinal advancing movement in a vertical plane, book-clamps carried thereby and 50 movable at right angles with respect to the conveyor movement, means for feeding books in the same direction and in parallelism with and beneath the open book-clamps at the beginning of the lower run of the 55 conveyor, and means for applying covers to the books during the lower run of the conveyor while held by the book clamps and travelling in a substantially horizontal straight-line path through the machine.

60 5. In a book covering machine, a continuously moving looped endless book conveyor having a lower forward run in a vertical plane, means for feeding books in horizontal alinement with the beginning of 65 the forward run of the conveyor, and a

70 delivery chute having inwardly tapered sides progressively approaching in mutual parallelism in horizontal alinement with said feeding means and lower run of the conveyor.

6. In a book covering machine, a continuously traveling book-clamp moving in a vertical plane, means for feeding books in alinement with said book-clamp, a delivery chute in horizontal alinement with 75 said feeding means and said book-clamp, and means for opening said book-clamp when approaching said chute.

7. In a book covering machine, a continuously traveling book-clamp moving in 80 a vertical plane, means for feeding books in alinement with said book-clamp, a delivery chute in alinement with and beneath said book-clamp, and means for opening said book-clamp when approaching said 85 chute.

8. In a book covering machine, a continuous traveling book-clamp moving in a vertical plane and in a substantially horizontal, straight-line path, means for feeding books in alinement with said book-clamp, means for applying a cover to the book held by said book-clamp, a delivery chute in alinement with said book-clamp, and means for opening said book-clamp 95 when approaching said chute.

9. In a book covering machine, a continuous traveling book-clamp moving in a vertical plane and in a substantially horizontal, straight-line path, means for feeding books in alinement with said book-clamp, means for applying a cover to the book held by said book-clamp, a delivery chute having inclined sides in alinement with said book-clamp, and means for opening said book-clamp when approaching said chute.

10. In a book covering machine, a continuously traveling, endless looped book conveyor moving in a vertical plane, movable 110 book-clamps carried thereby having an opening and closing movement at right angles to the conveyor movement, means for opening and closing the book-clamps at the beginning and end of the lower run of the 115 conveyor, means for feeding books in alinement with the book-clamps, and means for applying covers to the books while held by said book-clamps.

11. In a book covering machine, a continuously traveling, endless looped book conveyor moving in a vertical plane, movable book-clamps carried thereby having an opening and closing movement at right angles to the conveyor movement, means for opening and closing the book-clamps at the beginning and end of the lower run of the 125 conveyor, means for feeding books in upright position and in alinement with the book-clamps, and means for applying covers 130

- to the books while held by said book-clamps.
12. In a book covering machine, a continuously traveling, endless looped book conveyor moving in a vertical plane, movable book-clamps carried thereby having an opening and closing movement at right angles to the conveyor movement, means for opening and closing the book-clamps at the beginning and end of the lower run of the conveyor, means for feeding books in alignment with the book-clamps, means for applying covers to the books while held by said book-clamps, and a delivery chute in horizontally-extended alignment with the path of said book-clamps when holding the books.
13. In a book covering machine, a continuously traveling, endless looped book conveyor moving in a vertical plane, movable book-clamps carried thereby having an opening and closing movement at right angles to the conveyor movement, means for opening and closing the book-clamps at the beginning and end of the lower run of the conveyor, means for feeding books in alignment with the book-clamps, means for applying covers to the books while held by said book-clamps, and a delivery chute in horizontally-extended alignment with the feeding means and conveyor.
14. In a book covering machine, a book conveyor continuously travelling in a horizontal straight-line path in a vertical plane, means for feeding books thereto in horizontally-extended alignment with said conveyor path and a delivery chute also in horizontally-extended alignment with said conveyor path and feeding means.
15. In a book covering machine, a book conveyor continuously travelling in a horizontal straight-line path in a vertical plane, means for feeding books thereto in alignment with said conveyor path and a delivery chute also in horizontally-extended alignment with said conveyor or path, said feeding means and said chute being arranged beneath the lower run of said conveyor but in parallelism therewith.
16. In a book-covering machine, a loop endless conveyor continuously travelling in a vertical plane, a series of book-clamps carried thereon, each set being separately movable in mutual parallelism in a plane at right angles to that of the conveyor movement, and means for opening and closing said book-clamps only at the beginning and end of the lower run of the conveyor.
17. In a book-covering machine, a loop endless conveyor continuously travelling in a horizontal straight line path in a vertical plane, a series of book-clamps carried thereon, each set being separately movable in mutual parallelism in a plane at right angles to that of the conveyor movement, and means for opening and closing said book-clamps only at the beginning and end of the lower run of the conveyor.
18. In a book covering machine, an endless loop book conveyor travelling in its lower run in a horizontal straight line path in a vertical plane at a continuous uniform speed, glue applying means for the backs of the books arranged below said path, cover pressing means located in horizontal alignment with said glue-applying means, and means for feeding covers to said pressing means in timed relation with said conveyor.
19. In a book covering machine, an endless loop book conveyor travelling in its lower run in a horizontal straight line path in a vertical plane at a continuous uniform speed, glue applying means for the backs of the books arranged below said path, cover pressing means located in horizontal alignment with said glue applying means, means for feeding covers to said pressing means in timed relation with said conveyor, and a cover breaker and delivery chute also in horizontal alignment with said conveyor.

CHARLES A. JUENGST.
